UNITED STATES PATENT OFFICE

159,298

KNITTED FABRIC

Samuel Saftlas, Newark, N. J.

Application January 26, 1950, Serial No. 7,488

Term of patent 7 years

(Cl. D42—2)

To all whom it may concern:

Be it known that I, Samuel Saftlas, a citizen of the United States residing at Newark, in the county of Essex and State of New Jersey, have invented a new, original, and ornamental Design for a Knitted Fabric, of which the following is a specification, reference being had to the accompanying drawing, forming a part thereof.

Referring to the drawing:

The figure is a view of a knitted fabric embodying my new design.

I claim:

The ornamental design for a knitted fabric, as shown.

SAMUEL SAFTLAS.
